Primary Examiner — Kevin K Rudzinski*Assistant Examiner* — Evans David Delesline(74) Attorney, Agent, or Firm — Bochner PLLC; Andrew D Bochner; Eric R Kleinertz(57) CLAIM

The ornamental design for a ring, as shown and described.

DESCRIPTION

FIG. 1 is a top, front, right-side, perspective view of a ring;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

In the drawings, the broken lines are for the purpose of illustrating environment only, and form no part of the claimed design.

1 Claim, 4 Drawing Sheets(56)
